UNITED STATES PATENT OFFICE.

JOSEPH F. GLIDDEN, OF DEKALB, ILLINOIS.

DAM.

SPECIFICATION forming part of Letters Patent No. 678,105, dated July 9, 1901.

Application filed November 15, 1900. Serial No. 38,619. (No model.)

To all whom it may concern:

Be it known that I, JOSEPH F. GLIDDEN, of Dekalb, county of Dekalb, and State of Illinois, have invented certain new and useful 5 Improvements in Dams, of which the following is a specification.

My invention relates to dam constructions for the purpose of raising the level of the water in streams, small rivers, and like water-ways, and has for its principal object to produce a strong, durable, and highly economical construction of the class specified in which the economical feature is secured principally through the utilization of certain 15 waste materials as the chief element in the construction thereof, as hereinafter specified.

My invention in its structural characteristics combines the use of both masonry and metal, and for the latter I contemplate the 20 employment of the waste ends of wires found in the refuse and scrap heaps of wire-mills and wire-implement-making factories. The amount of short scrap-wire rejected by such mills and factories as unavailable for any 25 manufacturing purposes, and consequently consigned to the scrap heap, is very considerable, and I have found that such short waste ends of wire tied up in bundles of suitable size for convenient handling—say from six to 30 twelve inches in diameter—are excellently adapted when properly laid to form a main bed or body of a dam construction, such bundles being piled closely together in a compact mass across the stream.

35 The improved method and construction of dam forming the subject of my present invention is illustrated in the accompanying drawings, in which—

Figure 1 is a plan view of a dam built in 40 accordance with my invention, and Fig. 2 is a view of the same in vertical transverse section.

In constructing a dam in accordance with my invention I employ as the principal building agent bundles of scrap-wire A, which, as above stated, may be the tailings or refuse from wire-drawing or wire-implement-making mills and factories. These bundles of short wire are piled together in a thick compact mass across the bed of the stream B, the wires all being laid in a direction longitudinally of the current. The width and height

of this wire bed will of course be regulated by the height to which the water-level is to be raised and the water-pressure to be withstood. Directly behind the wire bed I erect 55 a backing or abutment of masonry C, preferably simply a roughly-built stone wall of a height at least equal to that of the wire bed. Both the wall and the bed will be given a 60 slight dip centrally thereof to provide an overflow for the water, and the entire dam thus constructed will have a gradual slope on its pressure-resisting side from its top to the bed of the stream, and this sloping face of the 65 dam will preferably be provided with a top covering of cement or earth, or both, as indicated at D and E. By reason of the fact that the ends of the wire, where refuse or scrap wire is employed, are more or less bent over 70 in hook form, the bundles when piled and pressed closely together become anchored to each other and form an extremely compact and tenacious mass almost impossible of separation by any pressure that may be brought 75 against it.

A dam constructed as described has been found in practice to possess a high degree of efficiency, especially as applied to small streams, and in view of the fact that the scrap-wire can be secured from the mills and factories at a merely nominal cost, while the other materials employed in the construction of the dam may usually be found close at hand at little or no expense, the entire cost 85 as regards materials used is obviously a minimum.

I do not limit myself to the use of waste or scrap wire, as new wire may of course be employed where the former cannot be had. 90

I claim as my invention—

1. A dam construction comprising a body or bed of short wire laid with the wires parallel with the stream, combined with a backing or abutment of masonry directly behind 95 said wire bed, substantially as described.

2. A dam construction comprising a body or bed formed of a number of bundles of short wire piled closely together, said bundles lying parallel with the stream, combined with a 100 backing or abutment of masonry directly behind said wire bed, and a covering of earth or cement or other suitable material imposed on said wire bed, substantially as described.

3. A dam construction comprising a body or bed formed of a number of bundles of short wire piled closely together, said bundles lying parallel with the stream, combined with a 5 backing or abutment of masonry directly behind said wire bed, and a covering of earth or cement or other suitable material imposed on said wire bed, the pressure-resisting face

of the dam having a gradual slope from the top of the masonry to the base of the dam, 10 substantially as described.

JOSEPH F. GLIDDEN.
